CLAIM

We claim, the ornamental design for a measurement device, as shown and described.

DESCRIPTION

FIG. 1 is a front top perspective view in accordance with an embodiment;

FIG. 2 is a rear bottom perspective view of the measurement device of FIG. 1;

FIG. 3 is a rear top perspective view of the measurement device of FIG. 1;

FIG. 4 is a front view of the measurement device of FIG. 1;

FIG. 5 is a rear view of the measurement device of FIG. 1;

FIG. 6 is a first side view of the measurement device of FIG. 1;

FIG. 7 is a second side view of the measurement device of FIG. 1;

FIG. 8 is a top view of the measurement device FIG. 1; and,

FIG. 9 is a bottom view of the measurement device of FIG. 1.

The broken lines shown in FIG. 1-FIG. 9 are not part of the claimed design.

References to "side", "top", "front", "rear" and "bottom" in the figure descriptions are not meant to require certain in-use orientation; a measurement device according to the claimed design may be used in any orientation.

1 Claim, 8 Drawing Sheets
